FLASHLAMP CONTAMINANT DETECTOR

Frederick William Harjes, Kew Gardens Hills, Norman P. Salz, Bayside, and John Warren Culp, Flushing, N. Y., assignors to Sylvania Electric Products, Inc., a corporation of Massachusetts

Application April 26, 1952, Serial No. 284,662

9 Claims. (Cl. 250—83.3)

This invention relates to a method and apparatus for the detection of contaminating gases within a sealed container. More particularly, it relates to a method and apparatus for detecting and measuring air as a contaminant in oxygen filled flash lamps.

In view of the fact that oxygen is present in flash lamps at pressures substantially less than atmospheric, usually in the neighborhood of from 37 to 58 cm. of mercury pressure depending on the lamp size, the lamps are prone to suck in any atmospheric gases if the lamps are not hermetically sealed. This is true even with very small cracks or leaks in the seal or envelope portions of the lamp. When such leaks occur the lamps are likely to explode when flashed in view of the high pressure which is developed when inert gases such as nitrogen which do not enter the reactions are heated by the combustion of the light giving material. For this reason it has been quite a common custom to test the completed lamps for the presence of air. Inasmuch as even small leaks may result in an appreciable increase in pressure over a long period of time such as would be the case when bulbs are kept on the shelf for some time before firing it has been the custom to make such tests after the expiration of several days after the bulbs have been completed. One well known method for conducting such a test is to excite the gases within the lamp with the aid of a standard high frequency coiler such as is customarily used in vacuum work. A blue green color of this discharge indicates a good lamp. One that has a purplish color, however, indicates the presence of atmospheric air. It is essential to use moistened electrodes pressed against the glass to insure good electrical contact and minimized air breakdown between the electrode and the lamp which, if it occurs, obscures the discharge. In this test the brightness of the discharge is so low that it must be observed in total darkness. Furthermore, the brightness is a function of such variables as electrode dampness, pressure of the gas within the bulb, contamination of the oxygen inside the bulb, and voltage across the electrodes. It is, therefore, difficult to see small variations of color under these circumstances. This method also has the serious drawback that the high frequency coiler occasionally flashes a bulb in front of the operator's dark adapted eyes. This not only disrupts the test program until the eye again becomes adapted to darkness but also causes a contraction of the iris which might in time cause considerable eye damage.

It is therefore, an object of this invention to provide a method and apparatus by means of which small contaminations can be detected and measured by a nondestructive method.

It is a further object of this invention to provide a method and apparatus which is mechanical and which has a high degree of sensitivity.

It has been found that in view of the fact that the spectral distribution of light from a gaseous discharge within a photoflash lamp is altered in the presence of air small contaminating quantities of foreign gases can be

2

measured accurately by permitting the light from the glowing flash lamp to fall on the cathode of a photomultiplier tube through an arrangement which will intermittently filter out certain light rays.

5 In the drawings which illustrate an embodiment of the method and apparatus of this invention;

Figure 1 is a schematic view showing the source of energy to induce the radio frequency discharge within a flash lamp, a pair of electrodes and a flash lamp in position therebetween;

Figure 2 is a front elevation partly in section showing the positions of a phototube, a revolving drum, a switch and motor;

Figure 3 is a preferred embodiment of a circuit diagram, and;

Figure 4 is a graph showing the curve obtained by plotting air pressure against resistance.

The non-destructive method of detecting and measuring air as a contaminant in oxygen filled flash lamps of this invention differs primarily from the method of the prior art in that a sensitive photomultiplier tube provided with a means for alternately scanning the total light output of the discharge and the light output less the ultraviolet rays is substituted for the eye of the observer.

15 25 The apparatus of this invention consists essentially of a means for generating high frequency energy, electrodes connected therewith, a phototube, and means for measuring the intensity and spectral character of a glow discharge.

30 35 The means for generating high frequency energy may consist of an oscillator such as shown at 10. This oscillator is adapted to produce energy of the type which will introduce a gaseous discharge within a flash lamp when electrodes such as 12 connected to the oscillator are placed in intimate contact with the envelope 14 of the flash lamp 16. These electrodes are preferably made of a sponge-like material having good current carrying characteristics.

40 The means for detecting and measuring the intensity and spectral character of the glow discharge may, for example, consist of a photomultiplier tube, means for intermittently filtering the light rays which strike the cathode of a photo tube and a bridge circuit connected therewith. In the embodiment illustrated in the drawings the means for intermittently filtering the light is shown as a

45 rotating drum 22 which is provided with two apertures one of which is covered with an ultraviolet absorbing gelatin filter 24. The rotatable drum 22 must naturally be provided with some means for rotation. This may be in the nature of a motor 30 connected to the drum 22 by means of a shaft 32. In order that the photo tube 20 can measure the light passing through the aperture provided with filter 24 and compare the two with one another a commutator switch 34 is mounted on shaft 32.

50 55 This switch, can naturally be replaced with any other switch capable of doing a similar job. In the preferred embodiment of the apparatus of this invention drum 22 is rotated at a speed of about 1800 R. P. M. During the measurement of a gaseous discharge through lamp 16 the photo tube has two alternate current components, one representing the total light output of the gaseous discharge and the other representing the visible light or the total light less the light absorbed by the ultraviolet absorbing filter 24. In order to properly evaluate the two currents the switch 34 mounted on the shaft 32

60 65 switches the two components synchronously to two branches of a bridge circuit as shown in Figure 3. The circuit consists of two photo tube load resistors R1 and R2 and a galvanometer G. The smaller current component, corresponding to the visible light output, is switched to a fixed resistor R1 (e. g. 1 megohm) and the larger current component, corresponding to the total light

70

of the gaseous discharge, is switched to a variable resistor R2 (e. g. 0-1 megohm). The variable resistor is adjusted until the galvanometer reaches zero current indicating that the average voltage drops across the two resistors are equal and, hence, the two resistors have the same ratio as the two components of current. The value of the variable resistance is therefore a measure of the degree of air contamination of the flashlamp.

Figure 4 of the drawings shows a curve which has been obtained by plotting the values of R2 obtained for varying amounts of air pressure in centimeters of mercury within a flash lamp. This curve can be referred to if so desired in determining the amount of air present in any selected bulb.

In practice the system of this invention may readily be used to indicate whether air pressure in a selected bulb is greater or less than a chosen tolerance level by setting the variable resistance to correspond to the chosen pressure. The galvanometer will then show a positive or negative deflection, according to whether the pressure is larger or smaller than the tolerance level. From this it is readily understandable that the galvanometer might readily be replaced by a device which would be actuated to perform one function when the deflection would be to the left and another function when the deflection is to the right and thus, for example, act to sort bulbs with permissible pressure from those where the pressure is excessive.

It has been found that the above-described method of air contamination detection is much more sensitive than any of the old methods. By this method it is possible to detect $\frac{1}{4}$ centimeter of air as opposed to the limit of 2 centimeters by the old method. The new apparatus is so much more sensitive than apparatus and procedures heretofore used that it can be used to check bulbs as they come off the production line thus enabling the operator to become aware of faulty techniques or equipment promptly and thus prevent the production of large quantities of poor grade bulbs. It also has the further advantages of eliminating human error which is inherent in visual detection.

From the foregoing, it will be appreciated that there is provided in accordance with this invention apparatus for measuring the concentration of air within the enclosed space 14 having a gaseous fill which includes a high frequency source 19 for producing a glow discharge within the enclosed space, a photo tube 20 positioned to intercept the light rays emitted from the enclosed space, a rotatable filtering means 22, 24 interposed between said enclosed space and said photo tube for intermittently filtering out any ultraviolet radiations emitted from the enclosed space whereby said photo tube provides one current component corresponding to the total light output of said glow discharge and a further current component corresponding to the visible light output of said glow discharge, a measuring circuit including bridge or measuring arms R1, R2, and switch or commutator means 34 operable in substantial synchronism with the filtering means and connected between the photo tube and the measuring circuit.

While the above description and drawings submitted herewith disclose a preferred and practical embodiment of the method and apparatus for the detection of contaminating gases of this invention it will be understood that the specific details of construction and arrangement of parts as shown and described are by way of illustration and are not to be construed as limiting the scope of the invention.

What is claimed is:

1. A contamination detector for a sealed transparent container having a gaseous fill including a source of high frequency energy for producing a glow discharge within said transparent container, photo-detecting means directed to intercept light emanating from said transparent container incident to said glow discharge, a bridge cir-

cuit including a null detector and first and second measuring arms, means for applying the output of said photo-detecting means alternately to said first and second measuring arms, and means interposed between said transparent container and said photo-detecting means for differentially filtering said intercepted light to provide light output in alternation to said photo-detecting means yielding a measure of the ultra-violet content of said intercepted light.

2. A contamination detector for a sealed bulb having a gaseous fill including a source of high frequency energy arranged to produce a gaseous discharge within said bulb, a single photomultiplier tube directed at a selected field within said bulb to intercept light emanating from said bulb incident to said gaseous discharge, said intercepted light having a band indicating the presence of air contamination in said gaseous discharge, a comparison circuit including a null detector and first and second measuring arms, means for applying the output of said photomultiplier tube alternately to said first and second measuring arms of said comparison circuit, and means interposed between said bulb and said photomultiplier tube for differentially filtering said intercepted light with respect to said band to provide light output in alternation to said photomultiplier tube yielding a measure of the presence of said band in said intercepted light.

3. A device for detecting air contamination of a sealed bulb having a gaseous fill including a source of high frequency energy for producing a gaseous discharge within said bulb, photo-detecting means responsive to the light produced by said gaseous discharge and producing a signal output dependent upon the spectral character of said gaseous discharge, the spectrum of said gaseous discharge having a band proportional to and indicative of the presence of air contamination within said sealed bulb signal-comparison means, means for applying said signal output of said photo-detecting means to said signal-comparison means, and means interposed between said bulb and said photo-detecting means for filtering the light produced by said gaseous discharge to provide light output in alternation to said photo-detecting means yielding a measure of said intercepted light.

4. A device for detecting air contamination in a sealed bulb having a gaseous fill comprising a source of high frequency energy for producing a gaseous discharge within said bulb, photo-detecting means responsive to the light produced by said gaseous discharge and producing a signal output dependent upon the spectral character of said gaseous discharge, the spectrum of said gaseous discharge having a band proportional to and indicative of the presence of air contamination within said sealed bulb, signal-comparison means, means for applying the signal output of said photo-detecting means to said signal-comparison means, and means for filtering the light produced by said gaseous discharge in advance of said photo-detecting means to provide light output to said photo-detecting means in alternation which upon comparison produced a voltage proportional to and indicative of the presence of air contamination within said sealed bulb.

5. The method of testing bulbs having a gaseous fill for air contamination including the steps of producing a glow discharge within said bulb, photoelectrically measuring the amount of visible light in said glow discharge to obtain a first signal, measuring the total light output of said glow discharge to obtain a second signal, balancing said signals against each other to obtain a third signal indicative of the ultra violet content in said glow discharge as a measure of air contamination of said gaseous fill, and rejecting bulbs indicative of excessive contamination as compared to a signal of known value adapted as a reference.

6. The method of testing bulbs having a gaseous fill for air contamination including the steps of producing a glow discharge within said bulb, photoelectrically measuring the amount of visible light in said glow dis-

charge to obtain a first signal, measuring the total light output of said glow discharge to obtain a second signal, and balancing said signals against each other to obtain a third signal indicative of the ultra-violet content in said glow discharge as a measure of air contamination of said gaseous fill.

7. The method of testing bulbs having a gaseous fill for air contamination including the steps of producing a glow discharge within said bulb, photoelectrically measuring the ratio of visible light in said glow discharge to the total light output of said glow discharge to obtain a signal indicative of the ultra violet content in said glow discharge as a measure of air contamination of said gaseous fill, and rejecting bulbs yielding a signal indicative of excessive contamination.

8. In apparatus for measuring the concentration of air within an enclosed space having a gaseous fill, means for producing a glow discharge within said enclosed space, a photo tube positioned to intercept light rays emitted from said enclosed space, filtering means interposed between said enclosed space and said photo tube for intermittently filtering out any ultraviolet radiation emitted from said enclosed space whereby said photo tube provides one current component corresponding to the total light output of said glow discharge and a further current component corresponding to the visible light output of said glow discharge, a measuring circuit, and switch means operable in substantial synchronism with said filtering means and connected between said photo tube and said measuring circuit and arranged to apply said one current 30 component and said further current component to said

measuring circuit to obtain the ratio of said total light output to said visible light output.

9. In apparatus for measuring the concentration of air within an enclosed space having a gaseous fill, means for 5 producing a glow discharge within said enclosed space, a photo tube positioned to intercept light rays emitted from said enclosed space, a rotatable drum having filtering means interposed between said enclosed space and said photo tube for intermittently filtering out any ultraviolet radiations emitted from said enclosed space whereby said photo tube provides one current component corresponding to the total light output of said glow discharge and a further current component corresponding to the visible light output of said glow discharge, a measuring circuit, 10 and switch means operable in substantial synchronism with said filtering means and connected between said photo tube and said measuring circuit for applying said one current component and said further current component to said measuring circuit.
